Des. 196,908
Patented Nov. 19, 1963

196,908

BELT BUCKLE

Henry R. Di Mascolo, 67 Crothers Ave.,
Cranston, R.I.

Filed Aug. 27, 1962, Ser. No. 71,461

Term of patent 3½ years

(Cl. D17—1)

FIG. 1

FIG. 2

FIG. 3

FIG. 4

FIG. 5

FIG. 1 is a front elevation of a belt buckle showing my new design.

FIG. 2 is an edge view thereof.

FIG. 3 is a side elevation thereof.

FIG. 4 is a rear elevation thereof.

FIG. 5 is an exploded perspective view showing the buckle in open position.

The dominant features of my design reside in the portions shown in solid lines.

I claim:

The design for a belt buckle, as shown and described.
